UNITED STATES PATENT OFFICE.

BENJAMIN IKOFSKY, OF BROOKLYN, AND JULIUS JOSEPHS, OF BRONX, NEW YORK.

SHAPE-RETAINING PACKING DEVICE.

Application filed September 23, 1927. Serial No. 221,438.

This invention relates to shape retaining packing device for caps and the like articles.

One object of the invention is to provide an improved shape retaining device for caps and the like articles for use in packing and shipping said caps or like articles, whereby delivery to the distributing dealer or purchaser may be made without the article or articles having been crushed, with said articles free from undesirable creases and in as perfect shape as they left the factory.

Another object of the invention is to provide an improved device of the character described for retaining a cap or like article, in proper folded "ready-to-wear" condition for transportation, without the usual pressing operation, the retaining means forming a covering for preventing coiling of the cap crown.

A further object of the invention is to provide a device of the character described which shall be of simple, inexpensive construction, easy and quick to apply, form a compact light weight package, and be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a perspective view of a receptacle or container, partly broken away to show caps packed therein in accordance with the invention.

Fig. 2 is a perspective view showing one of the shape retaining members applied to a folded cap.

Fig. 3 is a plan view of the improved shape retaining member.

Fig. 4 is an enlarged cross-sectional view of a cap in its retaining member as taken on line 4-4 in Fig. 1.

Fig. 5 is an enlarged fragmentary plan view showing the improved means embodied in the construction of the shape retaining member for holding the cap properly folded.

Fig. 6 is a perspective view showing a cap with the shape retaining member ap-

plied thereto enclosed in an envelope wrapper.

Fig. 7 is a perspective view showing a modified form of shape retaining member, embodying the invention applied to a folded cap.

Referring in detail to the drawing, in Fig. 1 is shown a receptacle or container 10 with the cover removed and partly broken away to show how a number of caps each held in a shape retaining member 11 embodying the invention may be piled into such container in one or more stacks, a partition 13 serving to prevent the stacks from shifting.

The shape retaining member 11 embodying the invention will now be described. Preferably, it is made of any suitable light, stiff, cheap sheet material such as cardboard and as here shown is rectangular shaped to conform to the space provided therefor in the container 10. Each member 11 has a pair of slits 11^a, parallelly spaced apart a distance less than the width of the cap for a purpose hereinafter to appear. Said slits terminate in openings 11^b which, by increasing the edge length along which the mid-portion 11^c pivots when the latter is pressed away from the adjacent end portions 11^d of the retaining member, for a purpose hereinafter appearing, increases the flexibility of the shape retaining member, and reduces the tearing strains to which the member 11 is subjected when same is applied to the cap 12.

The cap 12, to which the invention is shown applied, is of the outing class commonly known as a "sport" or "golf" cap. Said caps are generally made of cloth, commonly called and known in the art as, unfinished woolens, said cloth presenting a rough surface due to the woolen fibres which have not been milled down into the cloth in the same manner as the commonly known finished woolens. The cap 12 is shown to have the usual visor 12^a, with a front portion of the crown 12^b folded to overlie the visor in the well understood manner. In preparing such caps for shipment and distribution they are usually pressed with the back portion 12^c folded toward the visor and with side creases at 12^d so that the caps may be in ready to wear condition.

By employing the improved member 11 the necessity for pressing the caps into proper folded condition is eliminated. The

cap 12 is folded so that the back portions 12^a of the cap band are positioned approximately diametrically of the cap opening, the cap cloth of said band and back portions 5 in this position, being approximately flat surfaced, as is also the cap cloth of the crown portions of the cap. A plurality of cloth layers is thereby formed, joined at the ends thereof by a number of creases. Each 10 pair of adjacent creases is inserted into the opening of slit 11^a so that the line of the folded portion of said cap band will be approximately perpendicular to the line of the slit. The cap is thus retained in said 15 member 11, the cap crown being held against the mid-portion 11^c of the member 11, and the creased portions 12^a of the cap being secured in said slits against displacement, as is clearly shown in Figs. 2, 4 and 5. The 20 mid-portion 11^c covers the crown portions of the cap and prevents it from being soiled.

When the caps, with the members 11 applied to them, are stacked into the container 10, they are held against accidental displacement 25 by the edges of the member 11 contacting with the side walls of the container so that they may be shipped from the factory and distributed with assurance that they will not be crushed or wrinkled. Furthermore, it is a well-known fact that, when 30 two surfaces of such unfinished woolens as used in making these caps are brought into contact, the protruding fibres grip each other and upon sliding or otherwise moving one piece of cloth away from the other in 35 handling, a tearing of these fibres from one or the other piece of cloth takes place.

By the use of the member 11, the cap, while retained in the pressed and folded condition above described, and while providing 40 an easy means for readily removing the cap from a container or for carrying the cap about without necessarily touching the cap material, also prevents any portion of the 45 cap material from touching cap cloth of any other cap, thus avoiding the effect on the cloth above described.

In Fig. 6 is shown a cap 12 with the member 11 applied thereto, slipped into a 50 suitable bag or envelope wrapper 14 to make a compact unit package, forming a convenient means for carrying or storing the cap by the wearer.

A modified construction of the shape retaining member embodying the invention is 55 shown in Fig. 7. Here the retaining member 111 has the edge portions 111^a thereof

adjacent the slits 111^a, formed with reflexed and preferably down turned flaps 111^c which serve as means for spacing said members from each other when stacked. The mid-portion 111^c of said member covering the crown portion 12^b of the cap may be provided with a suitably shaped opening 111^b to expose a sufficient portion of the crown so that the pattern and color of the fabric forming the cap, and at the center of the crown, or any other distinctive portions having different effects than the back portions 12^a or the creased portions 12^a, which are apparent 70 at the slits 111^a, may be seen by a purchaser.

It will thus be seen that there is provided a device in which the several objects of this invention are achieved, and which is well adapted to meet the conditions of practical 75 use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. A cap-package comprising a relatively stiff flat member having a pair of elongated slits extending on opposite sides of a mid-portion thereof, and a cap having creased 90 portions inserted in said slits, the crown of the cap abutting said mid-portion.

2. In combination, a folded cap of the character described, a substantially stiff member having a plurality of slits formed therein, the folded edge portions of said cap being received in said slits, as and for the purpose described.

3. A shape retaining member of the character described made of flat, stiff sheet material having a pair of spaced slits, said slits being positioned to engage and hold a cap in folded position, the mid-portion of said member between said slits serving as a cover to guard the underlying portion of the cap against soiling, and reflexed flaps formed on opposite edge portions of said member for spacing a plurality of said members from one another in stacked relation.

In testimony whereof we affix our signatures.

BENJAMIN IKOFSKY,
JULIUS JOSEPHS.
